SAFETY DEVICE FOR FIREARMS

Sven Gunnar Olof Larsson, Huskvarna, Sweden, assignor to Huskvarna Vapenfabriks Aktiebolag, Huskvarna, Sweden, a corporation of Sweden

Application March 25, 1954, Serial No. 418,703

6 Claims. (Cl. 42—70)

This invention relates to a safety device for bolt-action firearms of the type in which the breech bolt is rotatable and movable endwise.

It is an object of the invention to provide a reliable and effective safety device which will lock both the sear and the breech bolt of the firearm. Another object is to provide a device of this kind of simple construction and ease of installation.

With the above and other objects in view, as will hereinafter appear, the invention comprises the novel combinations and arrangements of parts hereinafter set forth and illustrated in the accompanying drawing, in which:

Fig. 1 is a broken view in side elevation of a bolt-action provided with a safety device according to the invention.

Fig. 2 shows parts of the action in vertical longitudinal section.

Fig. 3 is a transverse section on the line III—III of Fig. 2.

Fig. 4 is a transverse section on the line IV—IV of Fig. 1.

In the drawing the invention is illustrated by way of example as incorporated in a sporting rifle action of the well-known Mauser type in which the breech bolt is rotatable and movable endwise, the endwise movement serving to eject the spent shell, reload the chamber and cock the firing member. In Fig. 1 the bolt is shown in retracted position and the safety device in its inoperative position. In Fig. 2 the bolt is shown in its foremost or firing position and the safety device in its locking or rearmost position.

With detailed reference to the drawing, the action comprises a substantially tubular breech casing 1 having a tail portion 2 and a loading-and-ejection opening 3. Mounted in the casing is a substantially cylindrical breech bolt 5 having an integral handle 6 and carrying a shell extractor 7. Formed integral with the bolt is a rear locking lug 8 projecting downwardly, when the bolt is in firing position, for engagement with a forwardly directed surface 9 provided in casing 1 and adapted to aid in bearing the explosion pressure axially exerted upon the bolt.

Slidably mounted in the bolt is a firing pin 10 pressed by a helical firing spring 11 and secured to a nut 12 which has an abutment 13 for cooperation with a cocking tooth 20 on the rear end of a sear which, in known manner, may be resiliently secured to the casing 1. In the embodiment shown the sear 17 is pivotally connected to the casing by means of a pin 18. A spring 19 in the sear forwardly of pivot pin 18 bears against the casing and urges the opposite rear end of the sear upwardly. The sear is apertured for receiving a trigger 15 which is pivotally secured to the sear by means of a pin 21 and which is formed with a pivot point 16 adapted to abut the portion 2 upon actuation of the trigger. A pressure on the trigger is transmitted to the sear through the pin 21 and the pivot point 16, forcing the rear of the sear downwardly against the action of spring 19. Simultaneously the cocking tooth 20 of the sear disengages from the abut-

ment 13 and thus releases the firing member comprising the parts 10 and 12. So far the bolt-action may be of well-known construction and operation without need of a more detailed description.

5 In the preferred embodiment shown the safety device comprises an elongated upright plate 25 mounted on the breech casing at one (the right) side of the sear 17 for slidable movement in the axial direction of the bolt. At its ends this plate is provided with upward extensions 10 26, 27. The rear extension 27 is movable in a lateral recess 36 in the tail part 2 and provided with a longitudinal slot 30 for a pin or screw 37 secured to said part 2 of the casing. Fixed to extension 27 is a thumb piece 28 arranged immediately above the tail part 2 beside the 15 breech bolt. The fore upward extension 26 is movable in a longitudinal groove or slot 35 (Fig. 2) in the bottom of the casing and may likewise be provided with a slot for a bearing pin mounted in the casing. Alternatively, the plate may, as shown, be reciprocably mounted on the 20 pivot pin 18 by means of a longitudinal slot 29 provided in the plate. A snap spring 38 fixed to the bottom side of the casing is adapted to cooperate with a pin 33 mounted on the safety plate, for keeping said plate either in its forward or inoperative position shown in Fig. 1, or in its 25 rearmost or locking position shown in Fig. 2 (wherein the rear part of the safety plate is broken away). At its rear end the safety member 25 should be provided with a locking part which, in the locking position of the safety, is situated in the path of movement of a 30 counterpart on the sear 17. In the embodiment shown this locking part, 32, is constituted by an angular slot 31 for a pin 39 fixed to the rear end of the sear. In the inoperative position shown in Fig. 1 this pin is movable downwardly in the slot during a firing movement of the 35 sear. In said inoperative position of the safety plate the top part of the plate extension 26 is situated in front of the path of the locking lug 8 corresponding to a turning movement of the breech bolt, which consequently, is not obstructed by the safety plate. By moving the safety 40 backwardly into the locking position shown in Fig. 2, a part of plate extension 26 is brought into said path of the lug 8 so as to engage the right side thereof whereby the breech bolt will become effectively locked in its firing position. Simultaneously the locking part 32 of the safety plate occupies a position immediately below the pin 39, thereby locking the sear 17 against a firing movement.

What I claim is:

1. A firearm comprising in combination: a breech casing, a breech bolt rotatable and axially displaceable in said casing, an integral handle and an integral rear locking lug on said breech bolt, a forwardly directed bearing surface in said casing engageable by said locking lug when the breech bolt is in firing position, a firing member carried by said breech bolt, a sear pivotally mounted on said casing for releasably holding said firing member in its cocked position, a trigger pivotally connected with said sear whereby motion of the trigger rotates the sear to release the firing member, and a manually operable safety member mounted on said casing for movement substantially in the axial direction of the bolt into and out of locking position with respect to the sear, said member in its locking position engaging one side of said lug to lock the breech bolt against rotation when the latter is in firing position.

2. A firearm comprising in combination: a breech casing, a breech bolt rotatable and axially displaceable in said casing, an integral handle and an integral rear locking lug on said breech bolt with the lug projecting downwardly when the breech bolt is in firing position, a forwardly directed bearing surface in said casing engageable by the lug when the bolt is in firing position, a firing member carried by said breech bolt, a sear pivotally mounted

on said casing for releasably holding said firing member in its cocked position, a trigger pivotally connected with said sear whereby motion of the trigger rotates the sear to release the firing member, and a manually operable safety device mounted on said casing at one side of the sear for slidable backward and forward movement into and out of locking position, a rear part of said device engaging said sear to lock the sear against firing movement and a forward part of said device extending into a slot in said casing to engage one side of said lug to lock the breech bolt against rotation when said device is in locking position.

3. A firearm comprising in combination: a breech casing, a breech bolt rotatable and axially displaceable in said casing, an integral handle and an integral rear locking lug on said breech bolt with the lug projecting downwardly when the breech bolt is in firing position, a forwardly directed bearing surface in said casing engageable by the lug when the bolt is in firing position, a firing member carried by said breech bolt, a sear pivotally mounted on said casing for releasably holding said firing member in its cocked position, said sear being provided at its rear end with a firing-member-engaging part and a lateral locking projection, a trigger pivoted to the sear whereby motion of the trigger rotates the sear to release the firing member, and a manually operable safety device mounted on said casing at one side of the sear for slidable backward and forward movement into and out of locking position, said safety device having a rear locking part for cooperation with said locking projection to lock the sear against firing movement in said locking position and a fore locking part projecting into a longitudinal slot in said casing for locking engagement with one side of said lug to lock the breech bolt against rotation when said device is in locking position.

4. A firearm comprising in combination: a breech casing having a tail portion, a breech bolt rotatable and axially displaceable in said casing, an integral handle and an integral rear locking lug on said breech bolt with the lug projecting downwardly when the breech bolt is in firing position, a forwardly directed bearing surface in the casing engageable by the lug when the breech bolt is in firing position, a firing member carried by said breech bolt, a sear pivotally mounted on said casing for releasably holding said firing member in its cocked position, said sear being provided at its rear end with a firing-mem-

ber-engaging part and a lateral locking projection, a trigger pivotally connected with said sear whereby motion of the trigger rotates the sear to release the firing member, a finger piece arranged on said tail portion beside the breech bolt, and an elongated safety plate mounted on said casing at one side of the sear for slidable backward and forward movement into and out of locking position; said plate having a rear upward extension movable in a lateral recess in the tail portion and secured to said finger piece, a fore upward extension movable in a slot in the bottom of the breech casing for locking engagement with one side of the lug to lock the breech bolt against rotation when the safety plate is in locking position, and a rear locking part for cooperation with said locking projection on the sear to lock the sear against firing movement in said locking position.

5. In a firearm the combination comprising a breech casing having an integral portion extending rearwardly, a bolt movable in translation and rotation in said casing, a lug formed on said bolt and arranged to depend therefrom when the said bolt is in firing position, a firing pin in said bolt, a sear pivotally mounted on said casing to releasably hold said firing pin in battery position, a trigger pivotally secured within said sear, whereby motion of said trigger rotates said sear to release said firing pin, and a safety device comprising a plate member slidably mounted on said casing at one side of said sear, a slot formed in said plate substantially in the form of an inverted L, a pin fixed to said sear and penetrating said slot whereby upon sliding said plate to safety inoperative position the pin moves vertically in the slot during sear pivoting and upon sliding said plate to safety operative position vertical motion of the pin and sear pivoting is prevented.

35 6. The invention as set forth in claim 5 including a forward portion formed on said plate member to move in interfering relation with said lug in safe position to lock the said bolt against rotation.
